PYROMETER BULB

Knud J. Knudsen, Middlebury, and Clarence I. McCall, Waterbury, Conn., assignors to Lewis Engineering Company, Naugatuck, Conn., a corporation of Connecticut

Filed Oct. 8, 1957, Ser. No. 688,944

4 Claims. (Cl. 73—339)

This invention relates to pyrometers or high temperature thermometers, and more particularly to the bulb structures of pyrometers.

With the advent of atomic reactors, nuclear equipment and the like, existing temperature measuring and controlling devices have no longer proved to be adequate or satisfactory. Problems not heretofore encountered, stemming from the use of radioactive fluids at high pressures and temperatures, must be considered and solved. Present temperature measuring bulbs having a high speed of response have not only been found to lack the necessary strength, but to lack sufficient ease of interchangeability or replacement of parts and sufficient resistance to corrosive influences. Moreover, such bulbs are not devoid of fissures, pockets or the like wherein radioactive matter can be lodged, to constitute satisfactory equipment which would minimize the possibility of subsequent injury or damage to operating personnel.

The above drawbacks and disadvantages of prior, existing pyrometer bulbs are obviated by the present invention, and one object of the invention is to provide a novel and improved pyrometer bulb adapted for immersion in rapidly flowing fluid held under high pressure, which bulb is highly resistant to vibration and failure resulting from turbulence and vibratory forces, while still retaining a rapid and desirable speed of response to temperature variations.

Another object of the invention is to provide a novel and improved pyrometer bulb and fitting construction in accordance with the above, which is devoid to the maximum extent of fissures, crevices or pockets wherein a contaminated fluid may become lodged and remain.

A further object of the invention is to provide an improved pyrometer bulb and fitting structure which is highly resistant to the corrosive action of a contaminated fluid exhibiting radioactivity.

A still further object of the present invention is to provide an improved pyrometer bulb and fitting structure as above characterized, wherein replacement of the bulb and the sensing element thereof may be effected with a maximum degree of ease and facility.

Another object of the invention is to provide an improved pyrometer bulb and fitting assembly for incorporation in a pipe line carrying contaminated fluid, which assembly is normally leak-proof at the proper operating pressures of the line and yet is adapted to permit a controlled leakage upon the fluid pressures rising to predetermined abnormal values.

A feature of the invention resides in the provision of a novel and improved pyrometer bulb and fitting structure having all of the above advantages and characteristics, and which is nevertheless relatively simple and economical in construction, and of the greatest reliability throughout an extended period of use.

Other features and advantages will hereinafter appear.

In the drawings accompanying this specification, similar characters of reference indicate corresponding parts wherever possible in the several views, in which:

Figure 1 is an axial sectional view of an improved pyrometer bulb with associated fitting structure and rapid response sensing element made in accordance with the invention.

5 Figure 2 is an axial sectional view of a fluid pipe line having incorporated therein the improved pyrometer bulb and fitting structure of Figure 1, said bulb and structure being shown in side elevation.

10 Figure 3 is an end elevational view of the bulb and fitting structure, looking at the connector end thereof.

Figure 4 is a fragmentary view of the outer end of the bulb and fitting structure, shown partly in elevation and partly in axial section and illustrating a modification of the invention.

15 Figure 5 is a fragmentary sectional view taken on line 5—5 of Figure 3, showing a part of the outer or lip portion only of the connector shell of this invention.

Figure 6 is a fragmentary sectional view showing part of the inner end portion of the connector shell, that located opposite to the end portion shown in Figure 5, and showing a welding bead on said inner end portion, provided to facilitate welding of the shell to the bulb body.

Considering first Figure 2, there is shown a pipe line 20 adapted to carry a stream of fluid such as the radioactive, contaminated cooling water of an atomic reactor. The flow of fluid in the line 20 is taken as in the direction indicated by the arrow. In one side wall, the pipe line 20 has an angularly disposed hollow projection or boss 21 provided with internal screw threads 22 for receiving an externally threaded bushing 23. The boss 21 is shown as having a sloping bore 24 intersecting the main passage of the pipe line 20 at an acute angle, illustrated as approximately 45°.

Normally, the cooling water is intended to flow in the line 20 at a rapid rate and under considerable pressures, and such water flowing against and around any projection, as for example a pyrometer bulb disposed in the passage, will cause turbulence and eddies, and will exert periodic forces against such bulb. Consequently a tendency to vibration is set up in the bulb, and we have found

40 that the thin-walled slim and elongate, rapid-response bulbs heretofore available suffered mechanical failure as a consequence of vibration. Prior bulbs under test were found to readily vibrate with a frequency of approximately 45 1000 cycles per second, and such relatively low vibration resulted in appreciable stressing and movement of the bulb, to the extent that cracking of the bulb jacket and ultimate failure would occur.

45 In accordance with the present invention there is provided, for mounting within the bushing 23, a novel and improved bulb structure which, while retaining the relatively thin walls necessary for rapid response of the sensing element to temperature changes, exhibits a much greater or higher natural frequency, having a resonant frequency in excess of 2000 cycles per second as compared

50 with the 1000 cycle per second frequency of prior pyrometer bulbs. In obtaining such appreciably higher resonant frequency, the present improved bulb employs a large-diameter stem portion adjacent its base and a novel, 55 tapered construction between the base and tip portions, facilitating its fabrication by means of stamping or drawing operations not requiring an anneal, and also attaining a desirable, minimum number of microcracks per square centimeter over its entire exposed surface. With 60 a bulb structure and shape as herein provided we have found, also, that erosion and wear are lessened and held to a minimum.

65 Referring to Figure 1, the bulb 26 shown therein comprises an elongate, tubular and hollow body having a closed end portion 27 of cylindrical shape and of a diameter commensurate with that of thin walled, rapid-response bulbs heretofore employed in pyrometers. The

bulb 26, however, has an open end portion 28 of enlarged diameter, appreciably greater than the diameter of the portion 27. Intermediate the end portions 27 and 28 the bulb body has a generally tapering configuration, and we have found it to be advantageous in making the bulb to provide a pair of tapered portions 29 and 30 separated by an intermediate cylindrical portion 31. The end portion 28 of enlarged diameter closely slidably fits in the bore of the bushing 23 as shown, so as to be rigidly supported thereby, and it will be noted from Figure 2 that the tip portion 27 of relatively small diameter is disposed substantially wholly in the path of fluid flowing through the pipe line 29, whereas the tapered portion 29 and intermediate cylindrical portion 31 are disposed partly in the path of the fluid, and partly out of said path. The tapered portion 30 and cylindrical end portion 28 of enlarged diameter are not disposed at all in the direct path of the fluid in the line 20.

Moreover, the extreme tip or extremity of the closed end portion 27 of the bulb is fabricated as indicated at 33, so as to have virtually a perfect radius, thereby to lessen eddies in the fluid flowing through the line 20.

We have found that with such a bulb construction the resonant frequency of vibration is more than doubled, as compared with a completely cylindrical bulb having a diameter commensurate with that of the tip portion 27, and that such doubled frequency may be higher than 2000 cycles per second. Accordingly, the degree of deflection of the bulb 26 is greatly lessened, so much so that mechanical failure due to vibratory forces and conditions caused by the turbulence and pressure of the fluid flowing through the line 20 will not result in mechanical failure of the bulb.

The wall thickness of the bulb 26 is preferably on the order of .010", at the closed end portion 27, thereby to make possible rapid response of the sensing element to temperature changes, while at the base portion of the bulb the wall thickness may be on the order of .012". Within the closed portion 27 there is disposed a thin insulated sleeve of woven glass fibers 35 impregnated with a silicone compound, such sleeve having a thickness on the order of .003". Inside the sleeve 35 there is located a sensing element or coil 36 having terminal wires 37 and 38 connected respectively through suitable leads, indicated generally at 40, to connector or terminal pins 41 mounted in glass bushings 43 and 44 carried by a supporting disc 45.

The slender tip portion 27 of the bulb 26 may have a nominal diameter on the order of $\frac{1}{4}$ of an inch, the intermediate cylindrical portion 31 may have a diameter on the order of $\frac{3}{8}$ of an inch, and the cylindrical portion 28 may have a diameter of $\frac{1}{2}$ inch. In conjunction with such diameters, the cylindrical portion 27 may be $1\frac{1}{4}$ inches in length, and the overall length of the bulb structure may be on the order of $3\frac{3}{16}$ inches. Measuring from the juncture between the cylindrical portion 31 and the tapered portion 30 to the outer or flanged end of the bulb 26, the dimension may be $1\frac{1}{16}$ of an inch.

In forming the bulb 26 a very large number of drawing operations is preferably employed, without the use of annealing between the various drawing steps. Instead, the amount of draw in succeeding steps is kept to a small value. By such procedure the bulb 26 work hardens and develops a grain in a longitudinal direction which, we have found, results in a minimum number of microcracks per unit surface area. Preferably, the entire outside surface of the bulb 26 is perfectly smooth and free from all burrs, blemishes, scratches and tool marks, and a microfinish may be obtained by the use of suitable compound wheels or the like. Where, as in the present instance, the drawing procedure is carried out without resorting to intermediate annealing steps, the resultant work-hardened material has a desirable toughness which not only facilitates microfinishing of the surface, but also enhances the mechanical strength and resistance to

destructive vibratory forces. We have found that a bulb such as that shown in Figure 1 may be advantageously formed, with such plurality of drawing operations, from soft Monel metal of the deep-drawing, corrosion-resistant grade.

Also in conjunction with the bushing 23 there is provided a connector shell 47 and a locking collar 48 surrounding the latter and adapted to secure the same to the bushing 23, said shell and collar constituting part of the fitting structure for supporting the bulb 26 and effecting electrical connection thereto.

As shown in Figure 2, the bushing 23 has an hexagonal shouldered portion 50 by which a wrench may be applied to it for tightening and loosening the same, and against said shouldered portion an annular sealing ring 51 of silicone composition may be disposed, for accommodation in an annular recess 52 in the boss 21. Further, an annular ring of silicone composition 52a may be provided in an internal annular recess 53 in the bushing 23, for engagement with the exterior wall of the enlarged portion 28 of the bulb 26 to provide a snug mounting for the bulb and to effect a seal for all normal conditions of pressure of the fluid in the line 20. Where line pressures exceed normal, the ring 52a may yield to permit a controlled leakage.

The connector shell 47 has an externally threaded end portion 42 adapted to accommodate the internally threaded collar of a cooperable female electrical fitting (not shown) by which electrical connections are effected to the terminal pins 41.

At its open end, the bulb 26 has an outturned flange 54 accommodated in an enlarged bore of a skirt portion 55 of the bushing 23, said enlarged bore terminating at an internal abutment shoulder engaged by a sealing washer, as will now be explained. Within said skirt portion there is further provided an annular elastic sealing washer 57, engaging the flange 54 of the bulb 26 and also engaging, as seen in Fig. 1, the internal abutment shoulder of the bushing 23 which is located above the washer 57 and is spaced above the flange 54. The washer 57 may constitute a tight seal, if such should be desired, or it may constitute a virtually non-sealing resilient element or member. The washer 57 is operable in conjunction with the locking and releasing action of the locking collar 48, as will now be further explained.

For the purpose of releasably mounting the bulb 26 in the bushing 23 and to facilitate quick release and/or locking of said bulb, the skirt 55 of the bushing 23 is provided with a pair of oppositely disposed bayonet slots 59 accommodating bayonet pins or projections 60, which latter are carried by the locking collar 48 and project radially outward therefrom along a diametric line. The collar 48 slidably fits on the connector shell 47 and engages an outwardly extending flange 62 of said shell, as seen in Figure 1, said collar being retained in place by a usual type of retaining ring 63 disposed in an annular groove in the shell.

For the purpose of easily and quickly manipulating the locking collar 48, as by turning the same to lock or release it, there is provided a pair of oppositely disposed, manually engageable lugs 65 having sufficient length to provide a secure finger grip.

With the above assemblage the resilient annulus 57 will be under compression as viewed in Figure 1, and will retain the bayonet pins 60 in their locked positions in the slots 59. Upon the locking collar 48 being turned counterclockwise, as viewed in Figure 3, the annulus 57 will suffer a slight compression due to inward axial movement of the collar and the connector shell 47, and thereafter the collar and shell will become free, for removal from the bushing 23.

If the sealing washer 57 is made to have a tight fit about the enlarged portion 28 of the bulb 26, and if it contains sufficient mass to virtually completely fill the space existing between the flange 54 and the shouldered portion 50

a tight seal will be effected between such parts when the collar 48 is attached to the bushing 23. Or, as shown in Figure 1, the sealing washer 57 may have a lesser mass so as to not completely fill the space between the flange 54 and the shoulder portion 50, in which case a controlled leakage may occur past the sealing washer upon excessive pressures being encountered in the line 20.

It will now be understood that when the bulb 26 is suitably fastened to the connector shell 47 the assemblage of bulb, shell and locking collar 48 may be readily, quickly removed from the bushing 23 for replacement or servicing, as conditions require.

In accordance with the present invention the bulb 26 and shell 47 are so fabricated and joined as to present a minimum number of exposed cracks, crevices or pockets in which contaminating fluid may remain to cause injury to personnel servicing the equipment. In attaining this objective we effect a complete, annular sealing weld between the flange 54 of the bulb 26 and the connector shell 47, thereby to obtain an integral junction between these two components. Preferably the connector shell 47 is also formed of Monel metal, and to avoid introducing a different kind of metal by the welding procedure, whereby electrolytic action or corrosion might occur due to the radioactivity or chemical composition of the contaminated fluid, the welding is accomplished by a projection technique, utilizing the material of the components themselves. In accomplishing this, see Figure 6, the flange 62 of the connector shell 47 is provided with an annular rib or bead 67, and the flanges 54 and 62 are brought together in a manner to cause the bead 67 to melt and to fuse the said flanges into a solid, integral unit. The welded joint is then turned down, finished and polished, whereby it is devoid of any cracks or crevices. Thus, the assemblage of bulb 26 and connector shell 47 becomes in effect a unitary piece formed entirely of a single metal alloy, in the present instance, Monel metal.

As already mentioned above, the threaded portion 42 of the connector shell 47 is adapted to accommodate the threaded fitting collar of a cooperable female electrical fitting (not shown) which also generally includes a cooperable shell.

For the purpose of keying the connector shell 47 to the mentioned cooperable shell (not shown), an internal projecting lug 70 is provided adjacent the outer lip portion or end of the shell. To avoid the making of any pockets in the outer end surface, beyond those absolutely necessary, the projecting lug 70 is formed as an integral part of the shell in the following manner: When the shell is initially fabricated, it is turned from solid bar stock, and an internal annular rib is formed, having a cross section similar to that of the lug 70. Thereafter, all but a small portion of the rib is broached away, leaving only the lug remaining. Thus, as distinguished from prior constructions where the keying lug is formed by lancing inwardly a finger from a wall portion, the present improved keying structure leaves the outside annular end surface of the connector shell entirely devoid of any pockets or recesses whereby it constitutes a perfectly flat sealing surface.

Fig. 4 illustrates a modified structure made in accordance with the invention. As shown in this figure, the connector shell 47 is devoid of any retaining means such as the retainer ring 63 shown in Fig. 1, and instead the collar 48a is provided with a locking set screw 74 which may be tightened against the outside of the shell 47 to rigidly secure the collar thereto. With this construction the collar 48a will be immovable on the connector shell 47 at all times that the set screw 74 remains pulled up tight. With the construction shown in Fig. 1, the collar 48 may be turnable with respect to the connector shell 47 at all times. The construction of Fig. 1 may be of advantage when applying the bulb 26, shell 47 and collar 48 to the bushing 23, since a somewhat greater freedom

of movement is had by the collar 48 during the seating of the bayonet pins 60 in the bayonet slots 59.

It will thus be seen from the above construction that we have provided an improved pyrometer bulb structure which has a maximum degree of strength while still retaining a very rapid response characteristic. The bulb structure is so formed that it has a minimum number of cracks or crevices wherein a contaminating substance might become lodged, and by virtue of the welded construction there exists a minimum number of separate pieces, further making for maximum strength. By the use of Monel metal the effect of corrosive substances is reduced to a minimum, and through avoiding special brazing and soldering materials any electrolytic action is eliminated. By virtue of the double bayonet pin and slot construction making for ease of separation of the collar 48 and shell 47 from the bushing 23, replacement of the bulb may be readily, quickly effected. Also, by virtue of the fit of the elastic sealing washer 57 a controlled leakage of liquid may take place when excessive pressures are encountered in the pipe line, while at the same time a tight seal is possible for normal working pressures of the liquid.

Variations and modifications may be made within the scope of the claims, and portions of the improvements may be used without others.

We claim:

1. In combination, a pyrometer bulb structure for disposition in fluids contaminated with radioactivity, comprising an elongate tubular body closed at one end and open at the other end with an outturned flange at said other end, all portions of said body being integral with each other; a tubular connector shell adapted to coact with a cooperable electrical fitting, said shell having an inwardly disposed end and an outwardly disposed end, and containing electrical connector pins, the inwardly disposed end of the shell abutting the said open end of the bulb body, both said abutting ends being welded and fused together and constituting a junction devoid of cracks, said shell being externally threaded for accommodating a threaded fitting collar and the other end of the shell having an annular, perfectly flat sealing surface adapted to seal against a similar surface, said outwardly disposed end having an internal, inwardly extending projection formed integral therewith for keying purposes adjacent the said sealing surface, and the latter being continuous and unbroken; a mounting bushing adapted to receive and support said bulb body, said bushing having an internal annular abutment shoulder for positioning said body; a resilient sealing washer engaged with the said flange and annular abutment shoulder; and a turnable locking collar insertable in said bushing and adapted to receive through it the said connector shell for securing the same in said bushing without requiring turning of the shell and body, said locking collar having a pair of oppositely disposed bayonet projections and said bushing having a pair of cooperable bayonet slots for receiving said projections, thereby to establish a quick-acting locking and releasing connection between the bushing on the one hand and the bulb body, shell and collar on the other hand.

2. In combination, a pyrometer bulb structure for disposition in fluids contaminated with radioactivity, comprising an elongate tubular body closed at one end and open at the other end, all portions of said body being integral with each other; a tubular connector shell adapted to coact with a cooperable electrical fitting, said shell having an inwardly disposed end and an outwardly disposed end, and containing electrical connector pins, the inwardly disposed end of the shell abutting the said open end of the bulb body, both said abutting ends being welded and fused together and constituting a junction devoid of cracks, said shell being externally threaded for accommodating a threaded fitting collar and the outwardly disposed end of the shell having an annular, perfectly flat

sealing surface adapted to seal against a similar surface, said outwardly disposed end having an internal, inwardly extending projection formed integral therewith for keying purposes adjacent the said sealing surface, and the latter being continuous and unbroken; a mounting bushing adapted to receive and support said bulb body, said bushing having an internal annular abutment shoulder for positioning said body; and a locking collar insertable in said bushing and adapted to receive through it the said connector shell for securing the same in said bushing, said locking collar having a pair of oppositely disposed bayonet projections and said bushing having a pair of cooperable bayonet slots for receiving said projections, thereby to establish a quick-acting locking and releasing connection between the bushing on the one hand and the bulb body, shell and collar on the other hand, said connector shell having an external shoulder engaging one end of the locking collar, and having an annular groove adjacent the other end of the collar; and a removable retaining ring in said annular groove, providing an abutment for preventing removal of the collar from the shell.

3. In combination, a pyrometer bulb structure for disposition in fluids contaminated with radioactivity, comprising an elongate tubular body closed at one end and open at the other end, all portions of said body being integral with each other; a tubular connector shell having an inwardly disposed end and an outwardly disposed end, and adapted to coact with a cooperable electrical fitting, said shell containing electrical connector pins, the inwardly disposed end of the shell abutting the said open end of the bulb body, both said abutting ends being welded and fused together and constituting a junction devoid of cracks, said shell being externally threaded for accommodating a threaded fitting collar and the other end of the shell having an annular, perfectly flat sealing surface adapted to seal against a similar surface, said out-

wardly disposed end having an internal, inwardly extending projection formed integral therewith for keying purposes adjacent the said sealing surface, and the latter being continuous and unbroken; a mounting bushing adapted to receive and support said bulb body, said bushing having an internal annular abutment shoulder for positioning said body; and a locking collar insertable in said bushing and adapted to receive through it the said connector shell for securing the same in said bushing, said locking collar having a pair of oppositely disposed bayonet projections and said bushing having a pair of cooperable bayonet slots for receiving said projections, thereby to establish a quick-acting locking and releasing connection between the bushing on the one hand and the bulb body, shell and collar on the other hand, said locking collar having a set screw adapted to be tightened against the connector shell to prevent separation of said collar and shell.

4. The invention as defined in claim 3 in which the bulb body, connector shell, bushing, locking collar and welded junction between the shell and bulb body are constituted of non-corrosive Monel metal.
